UNITED STATES PATENT OFFICE.

JOSEPH HALL, OF CHELTENHAM, ENGLAND.

METHOD OF MAKING PIPES OF ARTIFICIAL STONE.

No. 809,680.

Specification of Letters Patent.

Patented Jan. 9, 1906.

Application filed October 5, 1903. Serial No. 175,847.

To all whom it may concern:

Be it known that I, JOSEPH HALL, a subject of the King of Great Britain and Ireland, residing at Cheltenham, in the county of Gloucester, England, have invented a Method of Making Pipes of Artificial Stone, of which the following is a specification.

This invention has reference to the manufacture from concrete or like material of armored and unarmored artificial-stone pipes suitable for use as drain-pipes, for lining wells, and for various other purposes; and it has for object to enable such pipes to be produced in a simple, rapid, and economical manner.

The invention consists for this purpose in a novel method of forming pipes of the kind referred to by the aid of centrifugal force, as hereinafter more fully described, and pointed out in the claims.

In carrying out the invention material such as stone, brick, burnt earth, burnt clay, waste pottery, furnace-clinker, cinder, or slag, or other like material or mixtures thereof is or are reduced to the condition of coarse sand and mixed in convenient proportions with lime or cement and water so as to form a concrete mixture having, say, the consistency of slurry. The mixture (hereinafter called the "concrete mixture") is fed into a mold that is capable of being set in rapid rotation and whereby it is caused under the action of centrifugal force to move outward and line the mold and form a pipe the external shape of which will correspond with the internal shape of the mold, the mold being adapted to allow of the rapid escape therethrough under the action of centrifugal force of water from the concrete mixture, so as to permit of the rapid formation of a pipe of a sufficiently dry and stiff nature to allow of its being quickly removed from the mold. To allow of the molded pipe being subjected to compression in order to further solidify it before removal from the mold, there is provided in connection with the mold an endwise-movable core that can be inserted within and withdrawn from the mold, which is made in sections that are normally pressed together by external springs, but are capable of moving outward to a limited extent, the arrangement being such that when the mold charged with concrete mixture is rapidly rotated and the core is introduced axially into it the concrete mixture will be thrown outwardly against the sections of the mold, which will also be moved outward and compress the springs, and after the con-

crete material has been molded to shape and the bulk of the water removed therefrom by centrifugal force the speed of rotation is gradually reduced and the springs allowed to react and press the sections of the mold inward, so as to cause the molded pipe to be compressed between the mold and the core. When it is desired to produce armored pipes of the kind referred to, metal, such as iron or steel in any convenient form—say, for example, in the form of wire wound spirally or made up into the form of a frame or cage or otherwise arranged—is placed in the mold, so as to become embedded in the concrete mixture placed therein, the amount of metal used depending upon the extra degree of strength it is desired to impart to the finished concrete pipe.

In the accompanying illustrative drawings, Figure 1 shows in central vertical section a rotary table, carrier, and driving means for supporting and rotating a mold for producing concrete pipes according to this invention. Figs. 2 and 3 are horizontal sections corresponding to the lines A A and B B, respectively, of Fig. 1. Fig. 4 is a vertical section corresponding to the line C C of Fig. 5; and Fig. 5, a horizontal section corresponding to the line D D of Fig. 4, showing an expandible mold. Fig. 6 shows the complete apparatus in side elevation and to a smaller scale than the preceding figures. Fig. 7 shows in side elevation a cage of spirally-wound wire suitable for strengthening or armoring a concrete pipe. Fig. 8 is a diagrammatic view showing a modification.

a is a plate or table secured, as by bolts and nuts *b*, to the upper end of a rotary vertical carrier composed of T-iron members *c*, that are firmly connected together by upper and lower channelled-iron rings *d* and an intermediate spirally-arranged channelled-iron strip *e*.

f is a driving-pulley that is of smaller diameter than the table and is secured to the lower ends of the vertical members *c*, which are bent inward to suit the smaller diameter of the pulley.

The combined table *a*, carrier, and driving-pulley *f* are supported on balls *g*, arranged immediately beneath the said table and driving-pulley and running on upper and lower circular ball-tracks *h*, that are connected to and carried by a fixed supporting-framework *m*.

n is a vertically-movable core arranged within the group of vertical members *c* of the

rotary carrier which serve as guides therefor, the said core being made of hollow cylindrical form with a conical top and open bottom. Secured to a centrally-arranged boss σ on the under side of the cone-shaped top of the core n is a tube p , that extends downwardly within and throughout the entire length of the core n and serves as a hydraulic cylinder.

- 10 q' is a piston or ram fixed on the upper end of a vertically-arranged stationary liquid-supply pipe r and formed with a hole s , that places the interior of the pipe r in communication with the interior of the pipe p above the piston, so that the core n can be raised by admitting liquid under pressure to the pipe p and lowered by allowing the liquid to escape therefrom.

15 q is a packing-ring between the piston q' and tube p .

20 The core n is preferably prevented from rotating in any convenient manner. For this purpose the fixed tube r may be made of flattened section and pass through an eye p' of corresponding shape fixed to the tube p .

25 Upon the rotary table a is placed a mold that is built up of a number of vertical sections t , each formed with flanged sides u and intermediate longitudinal or vertical ribs v . Between the junctions of each pair of sections t is placed a vertical length of T-iron w , so arranged that the web of the T-iron is located in recessed portions x of the corresponding adjacent flanges u , and the head of the T-iron fits into a recess formed between the adjacent sections, which are beveled near their edges, so that the interior of the mold formed by the sections and the heads of the T-irons w is of practically cylindrical shape.

30 The lower end of each section t of the mold is formed with an internal annular flange y and an external flange z . The internal diameter of the flange y is about equal to the external diameter of the core n and has a radial width

35 about equal to that of the pipes to be made. The external flange z is formed with slots z' , into which extend bolts z'' , fixed to the table a , so as to allow of the sections t of the mold moving radially outward to a small extent.

40 The upper ends of the sections t are each formed with an external flange 1 . Each vertical rib v is stepped at intervals, so as to form shoulders 2 and 3, and when the sections are placed together to form the complete mold

45 rings 4, of channel-iron, of different internal diameters are slipped over the top of the mold, the lowermost ring 4 which is of greatest internal diameter resting on the flanges z , the ring 4 of next greatest internal diameter resting on the shoulders 2, the next ring 4

50 the internal diameter of which is less than that of the one last mentioned resting on the shoulder 3, and the upper flange of the top ring 4 resting on the upper flange 1 of the sections t , the lower flange of the said ring 4 be-

ing of smaller internal diameter than the upper flange thereof, so as to clear the said flange 1 . Between each ring 4 and the mold-sections t are located springs 5, one for each section, so arranged as to force the sections t toward the center and hold them together when the mold is at rest.

55 The mold formed of the sections t being placed upon the table a (see Fig. 6) and secured to it in a vertical position by the bolts z'' , so that the several sections of the mold are free to move outwardly, and the cylindrical core n being lowered so as to bring its top about level with the said table, the operation of manufacturing an armored concrete pipe 80 is as follows: Concrete mixture of the kind hereinbefore described is poured into the mold, and at the same time a cylindrical cage of wire network or spiral of wire, Fig. 7, is placed concentrically within the mold. The plate a is then caused to rotate rapidly, and at the same time the core n is caused to rise in the concrete mixture within the mold. The rotation of the table a causes the concrete mixture to fly outwardly toward and line the inner surface of the mold, the sections of which, also under the same centrifugal influence, move out radially as far as the springs and encircling rings 4 will permit, water at this time escaping through the gaps formed between the lengths of T-iron w and the adjacent surfaces of the mold-sections t . After the core has been completely raised and the mold filled with concrete mixture and sufficient time has elapsed for the escape of the greater portion of the water from the mixture the speed of rotation is reduced, and gradually the pressure of the springs 5 forces the mold-sections t inwardly and compresses the still plastic concrete pipe between the mold and the core n . Excess of material is removed from the top of the mold by a strickle or otherwise to finish the upper end of the pipe to shape and length. After being subjected to the radial pressure for a few minutes the concrete partially sets and the core n is then withdrawn. The external mold, with the inclosed pipe, is removed and placed on one side for a time sufficient to allow the concrete to thoroughly set, and another mold is placed on the table for the production of another pipe. When it is not desired to produce armored pipes, the metal strengthening cage or spiral, Fig. 7, is omitted.

60 In some cases the mold may be made in one piece or in sections bolted together, in which case the springs 5, and surrounding rings 4 are omitted and suitable provision made in the mold, such as by forming it with small perforations, for the escape of water from the concrete mixture under the action of centrifugal action. Also the apparatus may in some cases be arranged otherwise than vertically—for example, horizontally. Fig. 8 shows an arrangement wherein the

hydraulic cylinder p is stationary and is located above the mold and carrier, the core being carried by a ram o , adapted to be moved within the cylinder p by hydraulic pressure. In this arrangement rotary movement of the core is prevented by means of a fixed shaft n' of square cross-section that extends through an eye p^2 into the hollow core.

As will be evident, the apparatus can be variously modified without departing from the spirit and scope of the invention so long as the method of operation described in the specification or the relative arrangement of parts shown in the drawings is adhered to.

15 What I claim is—

1. A method of manufacturing a concrete pipe, said method consisting in molding a moist concrete mixture to shape by centrifugal force and simultaneously removing liquid therefrom, compressing the molded pipe, and afterward allowing it to set.

2. A method of manufacturing a concrete pipe, said method consisting in molding a moist concrete mixture to shape by centrifugal force and simultaneously removing liquid therefrom, subjecting the molded pipe to external and internal pressure, and allowing the resulting pipe to set.

3. The herein-described method of manufacturing a concrete pipe, said method consisting in molding a moist concrete mixture to shape by centrifugal force, simultaneously

separating liquid therefrom, then subjecting the partly-finished pipe to radial inward pressure, and afterward allowing the pipe to set.

4. The herein-described method of manufacturing a concrete pipe, said method consisting in subjecting a liquid mass of concrete mixture to rotary motion and limiting its outward movement so as to cause it to assume the required tubular shape by centrifugal force, separating liquid from said mass during the rotary motion, compressing the partly-finished pipe externally while still rotating but at a slower speed, arresting the motion of said pipe, and allowing it to set.

5. The herein-described method of manufacturing a concrete pipe, said method consisting in molding a liquid mass of concrete to a tubular shape by centrifugal force and simultaneously removing water therefrom also by centrifugal force, subjecting the partly finished and dried pipe to external pressure while firmly supporting the inner surface thereof, and allowing said pipe to set.

Signed at Cheltenham, in the county of Gloucester, England, this 15th day of September, 1903.

JOSEPH HALL.
